(57) **CLAIM**

The ornamental design for a boat trailer, as shown and described.

DESCRIPTION

FIG. 1 is a back and right side perspective view of the boat trailer of the present invention;

FIG. 2 shows a right side view of the boat trailer of FIG. 1;
FIG. 3 shows a left side view of the boat trailer of FIG. 1;
FIG. 4 shows a back view of the boat trailer of FIG. 1;
FIG. 5 shows a front view of the boat trailer of FIG. 1;
FIG. 6 shows a top view of the boat trailer of FIG. 1; and,
FIG. 7 shows a bottom view of the boat trailer of FIG. 1.
The broken line showing of environment is for illustrative purposes only and forms no part of the claimed design.
